UNITED STATES PATENT OFFICE.

DANIEL S. COOKE, OF LOS ANGELES, CALIFORNIA, ASSIGNOR OF ONE-HALF TO CHARLES J. WALTER, OF LOS ANGELES, CALIFORNIA.

NON-REFILLABLE BOTTLE.

SPECIFICATION forming part of Letters Patent No. 758,298, dated April 26, 1904.

Application filed January 23, 1904. Serial No. 190,375. (No model.)

To all whom it may concern:

Be it known that I, DANIEL S. COOKE, a citizen of the United States, residing at Los Angeles, in the county of Los Angeles and State of California, have invented new and useful Improvements in Non-Refillable Bottles, of which the following is a specification.

The object of my invention is to provide a bottle that when it has once been filled and my device applied thereto may be emptied of its contents, but cannot be refilled. I accomplish this object by the mechanism described herein and illustrated in the accompanying drawings, in which—

15 Figure 1 is a central vertical section of the neck of a bottle with my device in central longitudinal section in place therein ready to receive the cement. Fig. 2 is a like view taken in a plane at right angles to the plane of Fig. 1, with cement around the same to hold it in place. Fig. 3 is a perspective view of my device removed from the neck of the bottle.

In the drawings, A is the neck of a bottle the bore of which preferably tapers inwardly to its junction with the body of the bottle, which taper is so slight as to be scarcely discernible in the drawings. In the neck of the bottle and at a sufficient distance from the mouth thereof to provide for the insertion of the cork therein to close it is my non-refillable device, which consists of the bulb B, having an aperture C in the bottom thereof. The portion of the bulb surrounding this port forms a valve-seat. This bulb is adapted to fit snugly in the bore of the neck of the bottle, so as to provide a tight joint between the bulb and the neck of the bottle. This bulb is provided with a neck B', having a curved outlet-channel D therein. This neck is so constructed that the sides thereof, as shown in Fig. 1, fit snugly against the neck of the bottle, so that the outlet-channel D extends across almost the entire transverse diameter of the neck of the bottle; but in the transverse distance across it is a very narrow channel. Within the bulb is the valve-gate E, which consists of a round ball, which is adapted to roll down and close port C in the bottom of the bulb when the bottle is in a vertical or inclined po-

sition, and thereby prevent any liquid from being poured back into the bottle.

In the use of my device the bottle is first filled, after which my non-refillable device is placed in position, as shown in the drawings, with the bulb closely fitting the neck of the bottle, after which plastic cement F may be poured into the neck of the bottle around the neck of the non-refillable device until it reaches to nearly the top of the same, and when such cement sets it cannot be removed from the neck of the bottle without destroying the non-refillable device. This non-refillable device may be made of glass, if desired, as the lower end can be left open for the insertion of the valve-gate, after which it may be heated and bent to form the valve-seat for the valve-gate. It will be observed that the curved neck of the bulb prevents the insertion of an instrument into the bulb to hold the valve-gate off the valve-seat to refill the bottle, and thereby a simple and efficient and inexpensive device is provided which will prevent the refilling of the bottle whose contents have been used up. It will also be observed that when the bottle is turned so as to pour its contents out that the same will flow readily through the narrow curved channel in the neck of the non-refillable device, as the valve-gate will only touch at one point on such outlet. If desired, the bulb and neck could be made of metal; but I prefer glass, as it is cheaper and more easily formed into appropriate shape. By elongating the bulb slightly, so that its sides would contact for some little distance with the neck of the bottle, the surfaces which contact could be ground, thereby making a ground-glass fit between the non-refillable device and the neck of the bottle.

The non-refillable device is placed in the neck of the bottle a sufficient distance below the top thereof to permit of the insertion therein of an ordinary cork (not shown) to prevent the contents from leaking when shipping same.

Having described my invention, what I claim as new, and desire to secure by Letters Patent, is—

1. The combination with a bottle of a non-refillable device consisting of a bulb in the

neck of the bottle, said bulb having an aperture in the lower part thereof and a curved outlet at the other end thereof, said outlet extending almost across the transverse diameter 5 of the neck of the bottle and being very narrow transversely; a valve in said bulb adapted to close the aperture in the bottom thereof when the bottle is in a vertical position.

2. The combination with a bottle of a non-refillable device adapted to fit into the neck of 10 the bottle which device consists of a bulb having an aperture in the lower end thereof and a neck on the upper part thereof, said neck

having a wide curved outlet therein, said outlet being very narrow transversely; a ball-valve in said bulb adapted to close the aperture in the bottom thereof when the bottle is in the vertical position. 15

In witness that I claim the foregoing I have hereunto subscribed my name this 18th day 20 of January, 1904.

DANIEL S. COOKE.
